CLAIM

The ornamental design for a folded wheel block, as shown and described.

DESCRIPTION

FIG. 1 is a perspective view of the folded wheel block showing my new design;

FIG. 2 is an enlarged top plan view thereof;

FIG. 3 is a side elevational view thereof, the opposite side being a mirror image of that shown;

FIG. 4 is a bottom plan view thereof;

FIG. 5 is an end elevational view of the right end of FIG. 3;

FIG. 6 is a left elevational end view of FIG. 3; and

FIG. 7 is an enlarged fragmentary sectional view taken along the line 7—7 of FIG. 4.

FIG. 1

FIG. 2

FIG. 5

FIG. 6

FIG. 7

FIG. 3

FIG. 4
